UNITED STATES PATENT OFFICE.

MATHEW H. STOLL, OF LA CROSSE, WISCONSIN.

HINGE.

1,138,025.

Specification of Letters Patent.

Patented May 4, 1915.

Application filed January 2, 1915. Serial No. 132.

To all whom it may concern:

Be it known that I, MATHEW H. STOLL, a citizen of the United States, residing at La Crosse, in the county of La Crosse and State 5 of Wisconsin, have invented certain new and useful Improvements in Hinges, of which the following is a specification, reference being had to the accompanying drawings.

My invention relates to hinges and particularly to box hinges.

The primary object of my invention is the provision of a very simple, easily made, and extremely effective hinge so constructed that when the hinge is in place it is practically impossible to open the knuckle formed on one of the leaves of the hinge and thus detaching the hinge leaves from each other.

A further object of the invention is to so construct the hinge that when the hinge is in place upon a box the joint formed between the extremity of the knuckle and the body of the leaf on which the knuckle is formed will be entirely concealed and so disposed as to make it impossible to insert a screw 25 driver, chisel, or like implement into the said joint and open it.

My invention is illustrated in the accompanying drawings, in which—

Figure 1 is a vertical sectional view of a 30 box and a lid therefor showing my improved hinge applied thereto, Fig. 2 is a fragmentary perspective view of the two members of the hinge, and Fig. 3 is a face view of the hinge looking toward the bead 6.

Referring to these drawings, A designates a box of any suitable character, and B designates a cover of a box. My improved hinge comprises the leaf 2 which is adapted to be attached to the body of the box and the 40 leaf 3 which is adapted to be attached to the lid of the box. The leaf 2 is formed of thin sheet metal angularly bent at one end as at 4 and reduced in width at 5 and then bent around to form the knuckle 6. The 45 extremity of the metal forming the knuckle is abutted against the face of the reduced portion 5 as shown clearly in Fig. 1. The leaf 3 is also formed of thin sheet metal having the same width as the leaf 2 and is 50 angularly bent at 8. The portion 8 is disposed at an obtuse angle to the body of the leaf and its ends are rounded. Formed within this obtusely angular portion 8 is a longitudinal slot 9 having a length just 55 equal to the width of the tongue 5 so that when the reduced tongue portion 5 of the

leaf 2 is inserted within the slot the leaves 2 and 3 will be held from relative lateral movement.

In practical use the leaf 2 is disposed on 60 the inside face of the box A with the angular portion 4 bearing against the edge of the box. The leaf 3 is disposed upon the inside face of the lid B adjacent the inner corner of the lid and with the obtusely angular 65 portion 8 projecting slightly beyond the inner edge of the lid. The leaves are attached to the box and lid in any desired manner so that they can be readily removed, and in assembling the parts, the tongues 5 70 are inserted through the slots 9 of the leaves 3 and the tongues 5 are rolled up to form the beads 6. The joint 7 between the knuckle 6 and the tongue 5 is disposed immediately adjacent to the edge of the box and in 75 such position that it is practically impossible to force any instrument into this joint to open up the bead. In other hinges of more or less the same character known to me it is possible to insert an instrument between the 80 extremity of the leaf 3 and the under face of the tongue forming the knuckle 6 and then by twisting the instrument open up the knuckle, thus releasing the box cover so that the contents of the box may be removed 85 without unlocking the box.

It will be seen that with my improved hinge it is impossible to get such access to the knuckle as will permit the insertion of an implement at the joint of the knuckle 90 particularly when the lid is closed upon the body of the box.

It will be seen that my improved hinge may be very cheaply made, that the parts may be readily assembled and that the 95 hinge is entirely effective for the purpose designed.

Having described my invention what I claim is:

1. A hinge including two leaves, one leaf 100 being angularly bent adjacent one end, said angularly bent portion being formed with a transversely extending slot, the other leaf at one end being right angularly bent to engage over the upper edge of the wall of a 105 box and having a tongue projecting from said angularly bent end, the tongue having a width equal to the length of the slot formed in the other leaf, said tongue being inserted into the slot and being bent to 110 form a knuckle, the extremity of the tongue when so bent abutting against the inside

face of the tongue at the base thereof and immediately adjacent said slot.

2. The combination with a container having an upwardly extending side wall and a lid extending over and resting upon the upper edge of the side wall, of a hinge therefor comprising two leaves, one leaf being bent at right angles to and disposed upon the inner face of the side wall of the container with its angularly bent portion extending over the upper edge of the side wall, said leaf being formed with a tongue extending beyond the side wall, the other leaf being applied to the inner face of the lid and adapted to rest upon the angularly bent portion of the first named leaf, said second named leaf projecting beyond the lid and being angularly bent below the upper

edge of the side wall and transversely slotted to receive the tongue of the first named leaf, said tongue extending through the angular portion of the second named leaf from the inside to the outside thereof and being bent downward and then upward upon the inside face of the angular portion of the second named leaf to form a knuckle, the extremity of the tongue abutting against the inside face of the tongue at the base thereof adjacent to the said slot.

In testimony whereof I hereunto affix my signature in the presence of two witnesses.

MATHEW H. STOLL.
